ELECTROMAGNETIC OVERLOAD DEVICE.

1,305,937.

Specification of Letters Patent. Patented June 3, 1919.

Application filed July 6, 1917. Serial No. 178,928.

To all whom it may concern:

Be it known that I, CHARLES H. RIPPL, a citizen of the United States, residing at Cleveland, in the county of Cuyahoga and State of Ohio, have invented new and useful Improvements in Electromagnetic Overload Devices, of which the following is a specification.

This invention relates to electromagnetic 10 overload devices.

The principal object of this invention is to provide an electromagnetic overload device which, upon the occurrence of overload current conditions in its winding, will operate according to the following characteristics: If the current overload is between predetermined minimum and maximum limits, the device will operate at the end of a time interval after the occurrence of 20 the current overload, the time interval being inversely proportional to the degree of the overload; upon the occurrence of an overload above the said maximum, the time interval will abruptly disappear and the 25 contacts will operate substantially instantaneously; the minimum overload value, the length of the time interval, and the maximum overload value may each be adjusted independently of the others, and the maximum value and the time interval may also 30 be adjusted without materially affecting each other or the minimum overload value; during the time interval between the occurrence of an overload and the operation of the 35 device, if the overload subsides, the device will not operate, but automatically return to the condition prior to the occurrence of the overload.

Other objects will be apparent.

40 In the accompanying drawing, I have shown a front view, partly in section and broken away, of an overload device embodying my invention and adapted to open switch contacts when it operates.

45 Referring to the drawing, I have shown at 10 the energizing winding. The magnetic circuit energized by the winding 10 has a main frame 11, a stationary pole piece 12, a stationary thimble member 13, and a movable plunger 14. The pole piece 12 is adjustably threaded into the main frame at 15, and is adapted to be locked in any adjusted position by a lock-nut 16. The polar end of the pole piece 12 has a cone-shaped recess 17. The closed end of the magnetic 50

thimble member is exteriorly conical in shape as shown at 18, to correspond to the recess 17 in the pole piece, and is interiorly shaped to a horizontally transverse place as shown at 19, to correspond to the upper end 60 of the plunger 14. Two air gaps are thus formed, a gap 20 between the recess 17 in the pole piece 12 and the conical end 18 of the thimble member 13, and a gap 21 between the under side of the thimble head and 65 the upper end of the plunger 14. The side wall 22 of the magnetic thimble opposite the recess therein for the plunger 14 is of graded cross section, being thickest at the upper end where it joins the conical head 18, 70 and tapering off downwardly to a point adjacent to the upper end of the plunger 14 when in the normal position shown in the drawing. The thimble is held in position in the main frame 11 by a non-magnetic 75 nut 23, screwed into the main frame at 24, a flange 25 on the thimble being clamped between the nut and a shoulder 26 on the main frame. An internal shoulder 27 on the nut 23 serves as a stop to limit the 80 downward movement of the plunger 14. The plunger 14 carries a non-magnetic stem 28 riveted thereto at 46 and passing upwardly through the closed end of the thimble member 13 and through the pole piece 12, 85 terminating at 29 adjacent to a switch member to be described. The plunger 14 has a tail-piece 30 integral therewith, extending downwardly from the plunger through an opening 31 in the nut 23, and carrying the 90 non-magnetic piston 32 of a dashpot, the piston stem 33 being tubular and pinned to the tail-piece 30 at 34, and having lateral orifices 35. In the center of the piston is a ball valve 36. The cylinder of the dashpot 95 is shown at 37, and is filled with oil or other fluid medium up to the level marked "Oil level", the oil itself not being indicated on the drawing for the sake of clearness. The upper end of the cylinder of the dashpot terminates in a flange 38, by which the dashpot cylinder hangs on an internal shoulder 39 of an exteriorly threaded ring-nut 40, the ring nut in turn being supported by an interiorly threaded supporting nut 41, 100 threaded to the ring-nut 40 and to the nut 23. A dashpot nut 42 is adjustably threaded on the lower end of the dashpot cylinder 37, and is locked in any adjusted position by the lock-nut 43. Between the dashpot nut 105 110

42 and the ring-nut 40 is a compression spring 44. The dashpot cylinder is capable of movement vertically, the flange 38 sliding axially in the ring-nut 40, but the action 5 of the spring 44 normally holds it in its lowermost position, with the flange 38 on the shoulder 39 of the ring-nut 40. The relative axial position of the piston 32 and the cylinder 37 is adjustable by raising or lowering 10 the dashpot cylinder, this being accomplished by adjusting the position of the ring-nut 40 in the supporting nut 41, the adjustment being fixed by a lock-nut 45. The internal diameter of the cylinder 37 at 15 the lower end thereof is only slightly larger than the outside diameter of the piston, but the diameter of the upper end of the cylinder is considerably larger than the diameter of the piston, this greater diameter beginning abruptly at 45 for a purpose to be 20 described.

The parts thus far described are mounted on a slate, or other supporting means 50. Mounted on the same support is a movable 25 switch-arm 51, pivoted to the support at 52, and having a contact member 53. Mounted on the support 50 is a stationary contact 54, and when the switcharm 51 is in its normal position shown, the contact 53 engages the 30 contact 54. A stop 55 on the support limits the counter clockwise movement of the arm 51 when it has been moved to open the contacts 53—54. The switcharm 51 has also a finger 56, which normally lies adjacent to 35 the end 29 of the stem 28.

The operation of my invention may be described as follows: With the parts in the position shown, which is the normal unenergized position, if current of a suitable 40 value, to be described, flows in the winding 10, the magnetic flux in the gap 21 will lift the plunger 14 and cause the upper end 29 of the stem 28 to strike the finger 56 of the switcharm 51 and rotate the switcharm in 45 the counter clockwise direction, separating the contacts 53—54, the arm coming to rest against the stop 55. The minimum overload current at which the plunger 14 will be lifted, and the stem 28 will open the contacts, as above described, is predetermined 50 by the length of the adjustable air gap 20. When this value of current flows in the winding, the flux in the gap 21 is sufficient to lift the plunger 14 against its weight and 55 that of the stem 28 and tail piece 30, and the piston 32 attached thereto. The upward movement of the plunger 14 is retarded by the piston 32 in the usual manner, the rate of the movement being determined by the 60 rate of flow of the oil or other fluid around the edge of the piston from the space above the piston to that below it, the ball valve 36 preventing the flow of fluid through that valve. When the piston in moving up- 65 wardly passes the enlargement at 45, the

flow of fluid around it is thereby sufficiently increased to enable the piston to move practically freely. This gives a quick movement to the latter part of the travel of the stem 28, and enables the stem-end 29 to strike a 70 hammer blow against the finger 56. If, after the operation of the device, as just described, the winding 10 be deenergized, the plunger 14 and the piston 32 fall, this movement being unretarded due to the opening of the valve 36 and the free flow of the fluid into the stem 33 and out of it through the orifices 35 from the space below the piston to that above it. 75

If the overload in the winding 10 be above 80 a second predetermined value, the pull on the plunger and piston, and hence on the cylinder 37, will be so great as to compress the spring 44, whereupon the cylinder will be lifted along with the plunger and piston, 85 and the stem 28 will strike the finger 56 and open the contacts 53, 54, with practically no time interval. The predetermined value at which this instantaneous operation occurs is adjustable by adjusting the tension 90 of the spring 44, as hereinbefore described.

The length of the time interval above mentioned will be inversely proportional to the degree of the current overload between the minimum and maximum values for any one 95 adjustment. The length of the time interval for any given overload current value may be adjusted by adjusting the vertical position of the cylinder 37 with respect to the piston 32, as already described, which 100 correspondingly adjusts the distance between the piston in its normal position and the shoulder 45. It will be apparent that the adjustment of the time interval for any given current and the adjustment of the instantaneously operating overload current 105 value are independent of each other, and that the adjustment of one does not affect the adjustment of the other; nor does their adjustment affect the minimum overload 110 current value of the device. The adjustment of the gap 20, which, as heretofore mentioned, adjusts the minimum overload current value, will change the other two 115 adjustments mentioned, but these latter two can then be compensatively readjusted without changing the minimum current adjustment. 120

Upon the occurrence of an overload sufficient to lift the plunger 14, the flux in the magnetic circuit flows in the following path: from the main frame 11 into the plunger 14, and upwardly therethrough to the gap 21 where the flux divides, a small portion being diverted into the wall 22 of the 125 thimble, but, because of the restricted section of the thimble wall, the greater part passing across the air gap 21. The flux in the gap 21 exerts on the plunger a magnetic pull of a certain amount. As the 130

plunger moves upwardly, the section of the thimble wall lying opposite to the upper end of the plunger becomes greater and greater, so that a greater and greater proportion of flux is diverted into the thimble wall 22, and a smaller and smaller proportion passes across the air gap 21. However, since the upward movement of the plunger decreases the reluctance of the magnetic circuit as a whole, and the total amount of flux accordingly increases, the amount of flux passing across the air gap and causing magnetic pull on the plunger remains practically constant, with the result that at all positions of the plunger in its upward movement the magnetic pull thereon remains substantially constant. The absolute value of this constant pull is proportional to the degree of the overload, the minimum value being a pull barely able to raise the moving parts. If now, after the occurrence of the overload, and during the upward movement of the plunger, the current falls below the minimum overload value, the pull on the plunger, no matter where it may be in its upward movement, will become insufficient to hold it up and it will not continue its movement and open the contacts 53—54, but will return to its normal position. If the overload current be very large, or if it be at or above the value at which instantaneous operation occurs, the magnetic flux in the thimble wall will be sufficient to substantially saturate it, and therefore during the upward movement of the plunger the thimble wall will be unable to divert from the air gap 21 a greater and greater amount of flux, and therefore the pull in the gap 21 will increase so that the characteristic of the overload device to "reset" without operating should the current fall after the plunger has begun its upward movement will disappear and the plunger will inevitably complete its upward stroke.

For the sake of simplicity I have not shown or described the circuit connections of the winding 10 of the contacts 53—54, but as is well understood in the art, the contacts 53 and 54 may be employed to control a main line switch which in turn controls the current in the winding 10, so that when the device operates to open the contacts 53—54, the winding 10 thereupon becomes deenergized and the movable parts of the device return to their normal position.

My invention is not limited to the exact forms of the parts shown in the drawing, since many changes may be made therein without departing from the spirit of my invention or sacrificing its advantages.

I claim—

1. In an electromagnetic device, a magnetic circuit, an energizing winding therefor, a cylindrical core member in the circuit, there being a cylindrical working air-gap for the core member, and a magnetic member surrounding the gap and tapered externally in the direction opposite that which the movable member takes while closing the gap.

2. In an electromagnetic device, a winding, and a magnetic circuit energized thereby, the said circuit including a member external to the winding, a core member fixedly secured to the external member and having a cylindrical opening therein closed at one end, and a cylindrical movable core member in the opening, there being a working air-gap between the movable core member and the closed end of the fixed core member, the latter being tapered externally around the air-gap in the direction opposite that which the movable core member takes while closing the air-gap.

Signed at Cleveland, Ohio, this 30th day of June, 1917.

CHARLES H. RIPPL.
